ROTARY PUMP

Maurice Pelladeau, Paris, France, assignor of one-half to Standard Research Consultants, Inc., New York, N.Y.

Application December 21, 1956, Serial No. 629,940

Claims priority, application France December 21, 1955

11 Claims. (Cl. 103—4)

The present invention relates to a rotary pump, and more particularly to a rotary pump of the movable abutment type wherein a plurality of symmetrically formed pumping chambers are provided and cooperate with the movable abutments to produce a uniform pumping action entirely free of pulsations and to give a smooth, constant, continuous and uninterrupted volume and flow of fluid from the pump. The invention is a continuation-in-part of my application Serial No. 593,982, filed June 26, 1956.

The rotary pump embodied in the present invention is formed with a plurality of operating chambers which are formed with suction and discharge spaces defined by transversely movable abutments. The movable abutment type of rotary pump is generally recognized as giving satisfactory performance, but prior to the instant invention, this type of pump has not found great favor in industry due to the fact that it was unduly complicated and was generally uneconomical to operate for any extensive period. Moreover, the heretofore known rotary pumps were not capable of operating at high pressures for extended periods of time and were therefore undesirable for many necessary operations.

It is therefore an object of the present invention to provide a rotary pump of the movable abutment type which is simple in operation, economical to use and is capable of operating under high pressures for extended intervals of time.

Another object of the invention is to provide a rotary pump which includes a plurality of symmetrically formed operating chambers defined by adjacently positioned stationary and rotary members and which cooperate with movable abutments to effect a constant volume pumping action.

Still another object of the invention is to provide a series of fluid inlet and discharge passageways and ports in the stationary members which communicate with the operating chambers and which cooperate therewith and with the rotary members to produce the uniform pumping action.

A further object of the invention is to provide a pump which is formed with counter pressure chambers which are adapted to compensate for varying pressures on the lateral surfaces of the stationary members.

Other objects of the invention are: to provide a pump wherein pressures on the lateral surfaces of the rotary members are maintained in equilibrium; to provide a pump which includes a plurality of operating chambers that are constantly diminishing and increasing in volume at regular intervals, thereby providing for a constant volume delivery, free of pulsations; to provide a pump wherein the operating chambers formed therein are further defined by regions of tangency between the rotary and stationary members, and to provide effective fluid seals which limit lateral movement of the moving and stationary members.

Additional objects and the nature and advantages of the instant invention will be apparent from the follow-

2

ing description taken in conjunction with the accompanying drawings, wherein:

Figure 1 is a vertical sectional view of the housing of the pump embodied in the present invention, showing the inner pump elements in elevation.

Figure 2 is a view of pump similar to Figure 1 showing the relative position of the pump elements after the rotary members have been moved 90°.

Figure 3 is a sectional view taken along lines 3—3 in Figure 2.

Figure 4 is a partial vertical, sectional view of the pump taken along lines 4—4 in Figure 2.

Figure 5 is a partial vertical, sectional view taken along lines 5—5 in Figure 2.

Figure 6 is a sectional view of a rotating member.

Figure 7 is a partial elevational view of the rotating member shown in Figure 6.

Figure 8 is a vertical, sectional view of a modification of the invention, showing the inner pump element in elevation.

Figure 9 is a sectional view taken along the line 9—9 in Figure 8.

Figure 10 is a sectional view taken along the line 10—10 in Figure 8.

Figure 11 is an elevational view of a rotating member shown in Figure 8.

Figures 12, 13 and 14 represent views showing a modified form of abutment assembly.

Figure 15 is a diagrammatic view showing a linear development of a stationary member and rotary members located adjacent thereto.

Referring now to the drawings and particularly to Figures 1 to 3, the pump embodied in the invention is illustrated therein and is generally indicated at 10. The pump 10 comprises a cylindrical housing 12 which includes an integral end wall 14 having a fluid inlet pipe 16 suitably mounted therein. The opening side of the housing 12 is closed by an end plate 18 which is secured to the housing 12 by bolts 20 and which has an opening 18' formed therein for receiving a driven shaft 22.

As shown more clearly in Figure 3, the driven shaft 22 has an enlarged hub portion 24 integrally formed therewith, the hub portion 24 having an open end central chamber 26. One end of the shaft 22 is journaled for rotation in the end plate 18 and the hub 24 receives in the open end thereof an extension 30 integral with and protruding from the end wall 14. The extension 30 is formed with a frusto-conical opening 30' which communicates with the fluid inlet pipe 16 and the chamber 26 and the fluid medium is thus adapted to flow from the inlet pipe into the chamber 26 during the operation of the pump.

Positioned in the housing 12 and fixed to the walls thereof are a plurality of stationary ring members 32, 34 and 36. The end stationary ring member 32 is located adjacent the end wall 14 and is supported against movement relative thereto by one or more bolts 38. Similarly, the end stationary ring member 36 is located adjacent the end plate 18 and is fixed with respect thereto by one or more bolts 40. The central stationary ring member 34 is secured to the walls of the housing, intermediate the ring members 32 and 36, as seen in Figure 3, by bolts 42, only one of which is shown. The ring members 32 and 36 are both formed with projecting annular flanges 44 and 46, respectively, which form part of the fluid operating chambers as will herein be described. The central ring member 34 is formed with oppositely projecting annular flanges 48, 50 which cooperate with the annular flanges 44, 46 to define additional fluid operating chambers, as will hereinafter appear.

Located, in Figure 3, between the stationary ring members and secured to the hub 24 by keys 52 and 54 are

rotary ring members or rotors 56 and 58. The rotary ring members 56, 58 are identically formed and the configuration thereof is illustrated in Figures 6 and 7. As seen in Figure 6 these rotor members 56, 58 have the general appearance of a wedge or tapering configuration, but the outer face portions 59 and 60 thereof, are parallel and are disposed in perpendicular relation with respect to the horizontal axis of each member and of the pump.

The portions between these parallel faces are tapered. As will be described herein, the faces 60 define regions of tangency with the adjacent faces of the stationary members 52, 58. Formed in the side faces of the rotor 56 are oppositely facing annular grooves 61, 62 which receive therein the annular flanges 44 and 48, respectively. Similarly, the rotor 58 has the oppositely facing annular grooves 64, 66 formed in the side faces thereof for receiving therein the annular flanges 50 and 46, respectively. As seen in Figure 2, the tapered faces of the rotors, the stationary ring member flanges, the inner faces of the stationary ring members 32 and 36, and both faces of the stationary ring member 34, together with the housing 12, enclose a plurality of operating chambers which are indicated at 68, 70, 72 and 74. The operating chambers are separated by movable contact blades or abutments into suction spaces S1, S2, S3 and S4 and discharge spaces D1, D2, D3 and D4. These abutments or contact blades are arranged in pairs as shown in Figures 1 and 2 and are indicated at 75, 76; 77, 78; 79, 80; and 81, 82, and are located in contacting relation with the side faces of the rotors 56, 58. In order to positively urge the contact blades into engaging relation with the side faces of the rotors, leaf springs 83 are provided and are disposed in suitable grooves or cut out portions formed in the rotor members.

As shown in Figures 2 and 3, the blades 75, 76 and associated spring 83 are located in a notched portion 84 formed in the stationary ring member 32. The blades 81, 82 and associated spring 83 are located in a similarly formed notched portion 86 formed in the stationary ring member 36, and the blades 77, 78 and 79, 80 and associated springs 83 are located in a groove 88 which extends through the stationary ring member 34. The springs 83 positively urge the associated blades into firm contact with the side faces of the rotor members 56, 58, regardless of the position of said members. Thus, as illustrated in Figure 1, the springs 83 are compressed as the wider portion or face 60 of the wedge or cam shaped rings contacts the faces of the stationary members at a region of tangency. In Figure 2 the region of tangency is shown at the point where the face 60 makes contact with the cutout portion or grooves in which the blades 79, 80, 81, and 82 are disposed. In Figure 2 the face portions 59 of the rotor 56 are shown in position opposite the notched portions of the stationary ring members and the blades springs 83 urge the abutments 75, 76 and 77, 78 against the side faces 59 of the rotor member 56 and maintain firm contact therewith. Thus, as the rotor members 56 and 58 are rotated, the suction areas S1 to S4 rapidly and uniformly increase in volume while the discharge areas D1 to D4 of the operating chambers 68, 70, 72 and 74 rapidly and uniformly decrease in volume to effect a rapid and uniform pumping action of the fluid medium present, whereby the pumping action is free of pulsations and the operation thereof is constant.

The fluid medium is initially introduced into the operating chambers 68, 70, 72, 74 by way of conduit 16 and the hub central chamber 26, and then flows through port 92 into passage 90 (Figure 3) formed in the hub 24. Formed in the wall of the hub 24 and communicating with the passage 90 are ports 94, 96 and 98 which in turn communicate, respectively, with annular channels 100, 102 and 104. As shown in Figure 4, the annular channels 100, 102, 104 communicate with radial

channels 106, 108 and 110, which are formed in the walls of the stationary ring members 32, 34 and 36, respectively. The radial inlet channels 106, 108, 110 extend into short longitudinally running inlet channels 112, 114 and 116 which, in turn, communicate with the operating chambers 68, 70 and 72 and 74, respectively. Since the operating chambers 68, 70, 72 and 74 are separated into the suction and discharge spaces by the movable abutments or blades associated therewith, as shown in Figure 2, the inlet channels 112, 114, 116 communicate with the suction spaces S1, S2, S3 and S4, respectively, and direct the fluid medium thereto from the central chamber 26.

Referring now to Figure 5, the discharge passage system is illustrated and includes a plurality of short longitudinally extending discharge passages 118, 120 and 122 which are formed in the stationary members 32, 34 and 36, respectively, and which communicate with the discharge spaces D1, D2, D3 and D4 of the operating chambers 68, 70, 72 and 74 respectively. The discharge passages 118, 120 and 122 extend into short radial channels 124, 126 and 128, respectively, which in turn communicate with the annular discharge channels 130, 132 and 134 in the housing 12. The annular discharge channels 130, 132, 134 communicate with a longitudinally extending discharge passage 136 formed in the housing 12, the discharge passage 136 communicating with a discharge orifice or port 138. The discharge port 138 may be connected with any suitable discharge conduit to direct the fluid medium to any desired point remote from the pump.

It will be apparent that as the rotor members 56, 58 are rotated with the hub 24, the fluid medium present will be exhausted from the discharge spaces D1, D2, D3 and D4 of the associated operating chambers into the discharge channels and thence to the discharge passage 136.

By constructing the pump in the manner described and providing the operating chambers 68 and 70 on opposite sides of the rotary ring member 56 and operating chambers 72 and 74 on opposite sides of the rotary ring member 58, a balanced fluid system is formed. Thus, the pressure of the motive fluid in the operating chambers 68 and 70 is equal and lateral thrusts due to the pressure of the fluid are prevented from being impressed on the side faces of the rotary member 56. Similarly, the pressure of the fluid medium in the operating chambers is balanced and lateral thrusts on the side faces of the rotary member 58 are equalized.

In order to obtain a seal between the stationary and rotary members and, in addition, to prevent excessive lateral thrust on the end stationary members, fluid conducting chambers 140 and 142 are provided. As shown in Figure 3, the fluid conducting chamber 140 is formed between the side face of the stationary member 32 and the inner surface of the end wall 14 and communicates with the fluid discharge channels 130, as shown in Figure 5. Similarly, the fluid conducting chamber 142 on the opposite end of the pump is formed between the inner surface of the end plate 18 and the side face of the stationary member 36 and communicates with the fluid discharge channel 134. Thus the fluid in the pressure chamber is maintained at the pressure of the discharge fluid and therefore balances the thrust exerted on the stationary members by the pressure of the fluid in the operating chambers 68 and 72 respectively. Sealing rings 144 and 146 are located in grooves formed in the end wall 14 and end plate 18, respectively, and serve to prevent leakage of the high pressure fluid into the inlet chamber 26.

Lubricating means is also provided for the rotating hub 24 and includes a longitudinally extending passage 150 formed in the solid portion of the hub adjacent the shaft 22. Leading from passage 150 are radial passages 152, 154 which direct low pressure fluid from the cham-

ber 26 to the space 156 between the stationary end plate 18, stationary ring 36 and rotary hub 24. The fluid in the space 156 tends to cushion the hub 24 and in so doing acts as a lubricant. The fluid is returned to the system by way of the annular channel 104 in stationary member 36.

The fluid which enters the chamber 142 may also return to the chamber 26 through the passage 150 provided the fluid pressure is sufficient to overcome the forces exerted by the centrifugal action of the pump. The fluid will then return to the chamber 26 by way of passages 92, 90, 104, 152, 154 and 150. Although the fluid that is normally pumped is hydraulic fluid, which inherently acts to lubricate the pump elements, it will be clear that other fluids may be pumped through the device which also may act to lubricate the component parts of the pump.

A similar lubricating system is provided at the other end of the pump adjacent the extension 30, an annular fluid passage 158 being formed between the extension 30 and the hub 24. The passage 158 leads into the radial fluid return passage 160, which returns the low pressure fluid to the system by way of annular channel 100. A sealing ring 162 is disposed in an appropriately formed slot in the end plate 18 and prevents escape of the low pressure fluid along the shaft, while the sealing rings 144, 146 prevent the intermixing of the low and high pressure fluids. It will thus be seen that with fluid located in the end passages 156, 158 and 160, the hub will be retained in floating relation with end play minimized. The pump can then be subjected to relatively high pressure without undue wear while a constant, uniform and uninterrupted flow of fluid is maintained.

In operation, referring to Figure 3, the shaft 22 is rotated by a convenient source of power thereby rotating the hub 24 and the rotors 56 and 58 secured thereto. As the hub rotates fluid is directed through the inlet pipe 16 and extension 30 into the central chamber 26. The fluid then flows through port 92 into the passage 90 and is directed into the annular channels 100, 102 and 104 formed in the stationary members 32, 34, and 36, respectively.

From these annular channels the fluid is directed through the radial channels 106, 108, and 110, (Figure 4) and then flows into the suction space S1, S2, S3, S4 of the operating chambers 68, 70, 72 and 74, respectively, by way of the inlet channels 112, 114 and 116, as shown in Figures 1 and 4. As the rotors 56 and 58 are rotated, the parallel faces 60 formed on the wider portion of the wedge shaped members 56, 58 continuously contact the side faces of the adjacent stationary members to form a continuously sliding region of tangency. With the rotors revolving in the direction of the arrows indicated in Figure 1, the suction spaces S1, S2, S3 and S4 which are defined by the regions of tangency and the spring loaded contact blades or abutments alternately increase in volume to a maximum, the volume of the suction spaces then dropping instantaneously to zero, whereby a rapid pumping action free of pulsations is effected.

As the rotors 56, 58 rotate during the operation of the pump, the fluid is discharged from the discharge spaces D1, D2, D3 and D4 of the operating chambers in a continuous and uniform manner. The fluid exhausts from these spaces into the discharge passages 118, 120 and 122 whence it passes into the radial channels 124, 126 and 128, and discharge channels 130, 132, and 134, in Figure 5. The discharged fluid then flows into the common discharge passage 136 and out of the pump through discharge orifice 138.

Referring particularly to Figures 1 and 2, the various stages of the rotors 56, 58, are shown and in order to more clearly point out the mode of operation of the rotary pump, a single revolution of one of the rotors will be described with reference to the position of both rotors. Since the rotors are 180° out of phase all the stages of

one revolution are shown in Figures 1 and 2. Thus, in Figure 1, considering only the rotor 56, and the operating chamber 68, the suction space S1 is shown in a diminished position but moving in an increasing direction.

In Figure 2 the suction space S1 has increased in volume as the narrow parallel face 59 moves into contact with the abutment blades 75, 76. In Figure 1 the rotor 58 represents the next position which the rotor 56 assumes after a total movement of 180°. In this position the suction space S1 has further increased in volume, while the discharge space is diminishing in volume. In Figure 2, the rotor 58 represents the last stage of a complete revolution of the rotary member and shows the parallel faces 60 in contacting relation with the face of the adjacent stationary member, thereby cutting off the flow of fluid to the suction space and the discharge of fluid from the discharge space. At this point, the delivery from the operating chamber 68 is zero. Further rotation of the rotors 56, 58 moves them to the position shown in Figure 1 and the cycle is repeated as described.

Since the operating chamber 70 is symmetrical with the operating chamber 68, movement of the rotor 68 will force the fluid in the suction space S2 and discharge space D2 through the pump in the manner described above in connection with the operating chamber 68. In other words, the movement of the rotor 56 controls the flow of the fluid in the chambers on each side of it. However, since the rotary member 58 is 180° out of phase with the rotary member 56, the operating chambers 72 and 74 will continue to deliver fluid when the pump delivery of the operating chambers 68, 70 is zero. Therefore, the pump delivers a constant, uniform, and uninterrupted flow of fluid that is free of pulsations.

It will be seen that the spaces S1, S2, S3, and S4, in order to effectively act as suction chambers, must constantly increase in volume, and conversely the discharge spaces D1, D2, D3, and D4 must constantly decrease in volume to effectively discharge the fluid medium being pumped. The volume of the suction chambers thus increases progressively to a maximum and then is instantaneously reduced to zero, thereafter gradually increasing to maximum amount again. The discharge chambers gradually decrease in volume from a maximum to zero and then are instantaneously increased to a maximum amount, whereby the volume is again reduced in a uniform manner. The total volume of the suction chambers S1—S4 is always equal to the total volume of the exhaust or discharge chambers D1—D4 and this total volume is, of course, constant. In operation, as the rotary members 56, 58 are rotated in the direction of the arrow, as shown in Figure 2, the volume of the discharge chambers D3 and D4 is zero when the parallel faces 60 are tangential to the faces of the adjacent stationary members 34 and 36. The volume of the suction chambers S3 and S4 is then at a maximum; but as soon as the parallel surfaces move beyond the blades 79—82, the volume of the suction chambers S3 and S4 is decreased from a maximum amount to zero and the volume of the discharge chambers is increased from a zero to a maximum amount.

Referring now to Figure 15, the complementary chambers S2, S3 and D2, D3 are shown in linear development form. Assuming that the member 34 and blades 77—80 are rotating in the direction of the arrow, it will be clear that the volume of the suction chambers S2, S3 increases constantly up to a maximum point while the volume of the discharge chambers D2, D3 decreases uniformly to zero. The total volume of the suction spaces S2, S3 remains constant and is equal to the total volume of the discharge spaces D2, D3.

By providing a construction as described wherein the pressure of the fluid in the operating chambers 68 and 70 is equal and the pressure of the fluid in the operating chambers 72 and 74 is equal, the rotary members 56 and 58 are maintained in a state of equilibrium and endwise

movement thereof is substantially prevented. The fluid conducting chambers 140 and 142 further define a fluid seal for the pump and function to automatically take up any play which may occur in the stationary members. Thus, the pressure of the fluid in the fluid conducting chambers 140, 142 is the same as the pressure in the discharge passages 118 and 122 (Figure 5), respectively, and any tendency of the stationary members 32 or 34 to move laterally due to an increase or decrease of the pumping fluid will be automatically compensated for by the fluid in the chambers as described. It will thus be seen that the chambers 140, 142 further form a fluid seal for preventing ingress of air or egress of low pressure fluid. The low pressure fluid also acts to lubricate the spaces between the moving and stationary members and is returned to the system by way of the annular inlet channels 100 and 104.

In a modified form of the invention, as shown in Figures 8-14, it is contemplated to form the stationary members 32 and 36 integral with the end wall 14 and the end plate 18. In this simplified form of the invention, the channels and passages 100, 104, 106, 110, 112, 116, 118, 122, 124, 128, 130 and 134 would be eliminated and communication between the spaces or chambers S1, S2, and S3, S4 could be effected by forming a series of spaced openings and peripheral passages in the rotary members 56 and 58.

The peripheral passages would correspond generally to the position of the passages 106, 110, 118, 122 shown in Figures 1 and 2. Suitable inlet and exhaust passages would thus be formed in rotary and stationary members and the pump would operate as described above, the suction spaces increasing at a uniform rate and the discharge spaces decreasing at a uniform rate to effect a uniform pumping action.

It will be understood that the pump described herein may be operated at very high pressures since there are relatively few moving parts or elements subjected to wear. Moreover, the fluid seals and back pressure chambers are effective to maintain the high pressures at which the pump will operate without deforming or seizing and wear will be reduced to a minimum.

Referring now to Figures 8-10, a modified form of the invention, as mentioned above, is illustrated and includes a cylindrical housing 170 which has an integral end wall 172, having a fluid inlet pipe 174 mounted therein. The open end of the housing 170 receives a flanged end plate 176 which is secured to the housing 170 by bolts 178 and which has a suitably formed opening therein for receiving a driven shaft 180. As shown more clearly in Figures 8, 9 and 10, the shaft 180 has an enlarged hub portion 182 in which is formed a central chamber 184. The fluid inlet pipe 174 communicates with the chamber 184 and is adapted to supply the operating medium thereto. Centrally positioned in the housing 170 and fixed to the wall thereof by bolts 186 is a stationary ring member 188. On each side of the stationary ring member 188 are rotary ring members 190 and 192 which have a tapered configuration generally similar to the ring members 56, 58, described in connection with Figures 1-7. As shown in Figures 9 and 10, the annular grooves formed in the rotary ring members 190, 192 receive annular flanges 170a and 188a, respectively, formed in the casing end walls and in the stationary ring member 188.

The rotary ring members 190, 192 are also formed with flat portions 194, 196 which are located in parallel relation with respect to the faces of the stationary ring member 188 and are periodically moved into tangential relation therewith upon rotation of the rotary ring members.

As shown in Figure 8, operating chambers 198 and 204 are formed between the housing end walls and the outer faces of the rotary members 190, 192, while operating chambers 200 and 202 are formed between the inner faces of the rotary members 190, 192 and the lateral faces of the stationary member 188. In order to separate

the chambers 198-204 into suction and discharge spaces, movable abutments are provided and include abutments 206 and 208 which extend into grooves 210, 212 formed in the end walls 172, 176, respectively, and are biased against the outer faces of the rotary members 190, 192 by coil springs 214. Abutments 216, 218 are positioned in a slot 220 formed in the stationary member 188 and are biased against the inner faces of the rotary members 190, 192 by the coil spring 222. Thus, the movable abutments 206, 208, 216 and 218 separate the chambers 198-204 into suction spaces Sa, Sb, Sc and Sd and discharge spaces Da, Db, Dc and Dd.

The operating medium is introduced into the central chamber through the inlet pipe 174 and then enters a port 224, Figure 10, formed in the wall of the hollow portion of the enlarged hub 182, the port 224 communicating with an annular passage 226 which in turn communicates with a radial passage 228. The operating medium then enters an inlet passage 230 which communicates directly with the operating chambers 200 and 202. The outer chambers 198 and 204 do not receive the operating fluid directly, but communicate with the chambers 200 and 202 through a series of transverse channels 232 and peripheral slots 234 formed in the rotary members 190 and 192. In order to discharge the operating medium from the operating chambers a discharge passage 236, Figure 9, is formed in the stationary member 188, the passage 236 communicating with the discharge spaces Db and Dc. Connected to the discharge passage 236 is a radial passage 238 which is formed in part in the housing 170 and in part in the stationary member 188. The radial passage 238 is connected to a discharge conduit 240 and discharge port 242, these latter all being formed in the walls of the housing 170.

The operation of the device shown in Figures 8-10 is similar to the operation of the device described in connection with Figures 1-7 and it will be understood that the operating medium is constantly drawn into the suction spaces Sa, Sb, Sc, Sd through the passage 174 as these spaces increase progressively to a maximum.

At the same time, the fluid medium in the discharge spaces Da, Db, Dc, Dd is discharged at a constant rate through the discharge passage 236 as these latter spaces progressively decrease in volume. By providing the channels 232 and slots 234 in the body of the rotary members communication between the operating chambers is maintained, but the pump structure is simplified.

Referring now to Figures 12, 13 and 14, a modified form of the abutment members is shown and is illustrated generally at 244. Each abutment member 244 includes a grouping of three elements 246, 248 and 250 which are formed with convex outer edges. One side of the outer edge of each of the elements 246, 248, 250 engages the concave surface of the inner wall of the housing 170, and the other side of these elements engage the convex outer edge of the housing end walls and stationary member 188. (For a similar arrangement of the abutment, see Figure 3 as described herein.)

As shown in Figure 13, each element 246, 248, 250 is formed with a transverse slot 252 within which is disposed a cushion 254 of resilient material. The coil spring 256 is mounted on the cushion 254 and bears against the end surface of the grooves formed (210, 212, Figure 8) in the casing end walls or against the side wall of the adjacent abutments if the elements are located in the groove 220 of the stationary ring member, as in Figure 8. The coil spring 256 thus biases the abutment 244 into firm engagement with the lateral faces of the moving or rotary members 190, 192.

At rest, all of the elements 246, 248, 250 of the abutments 244 are in alignment as shown in Figure 12. However, during operation of the device the convex edges of the elements are adapted to shift laterally with respect to each other thereby deforming the resilient cushion 254. As shown in Figure 14, the central element 248 has been

shifted towards the outside with respect to the outer elements 246, 250, the inner edge of the central element 248 making firm contact against the convex inner surface of the adjacent operating chamber and the outer edge of the outer elements 246, 250 making firm contact with the concave outer surface of the operating chamber. Thus, by allowing the elements to shift laterally as described, firm engagement of the abutment members against the walls of the operating chamber will be maintained at all times.

It will be obvious to those skilled in this art that various changes may be made in construction and design without departing from the spirit of the invention, and therefore the invention is not limited to what is shown in the drawings and described in the specification, but only as indicated in the appended claims.

I claim:

1. A rotary pump comprising a housing, a drive shaft mounted for rotation in said housing, said drive shaft having a hub joined thereto with a chamber formed therein, at least one stationary member secured in said housing and formed with lateral faces, rotary members secured to said hub for rotation therewith and positioned in sealing contact with said stationary member so as to provide a pumping action therewith, each of said rotary members having a tapered configuration which defines a maximum and minimum thickness in the axial direction, the portions of said rotary members defining the maximum and minimum thickness being diametrically opposed, the portion defining the maximum thickness having parallel faces one of which engages one of the lateral faces of said stationary member to define regions of tangency therewith, the remaining portions of said rotary members being spaced from the lateral faces of said stationary members to define working chambers therewith, abutments disposed in said stationary member and contacting the lateral faces of said rotary members, means for urging said abutments into contacting relation with said lateral faces for separating said working chambers into suction and discharge spaces, inlet means formed in said stationary members and communicating with said suction spaces, discharge means formed in said housing and communicating with said discharge spaces, passage means communicating with the chamber in said shaft and with said inlet means for introducing fluid into said suction spaces, and fluid discharge passages formed in said stationary members and communicating with said discharge means for exhausting the fluid from said housing, relative rotation between said rotary members and stationary member causing said abutments to reciprocate while maintaining contact with the side faces of said rotary members, the volume of said discharge spaces being reduced uniformly from a maximum to a minimum and the volume of said suction spaces being increased from a minimum to a maximum whereby a uniform pumping action is effected, the sum of the volumes of the fluid being discharged and received remaining constant.

2. A rotary pump as set forth in claim 1, said urging means including springs secured to said stationary member and engaging said abutments for urging said abutments into contacting relation with the lateral faces of said rotary members.

3. A rotary pump as set forth in claim 1, which includes a plurality of stationary members similar to said first named stationary member and located in alternate relation with respect to said rotary members, sealing means disposed between said stationary members and rotary members, said sealing means being defined by sealing chambers located between said housing and adjacent stationary members, said sealing chambers communicating with said discharge means and receiving low pressure fluid therefrom, said fluid filled sealing chambers limiting axial movement of said stationary members and said rotary members.

4. A rotary machine as set forth in claim 1, said abut-

ments including a plurality of elements having a transverse groove formed therein, a cushion disposed in said groove, said cushion providing for relative movement of said elements upon contact of the edges of said elements with the surfaces of said working chambers.

5. In a rotary machine as set forth in claim 1, said rotary members being provided with passages in the body thereof, said passages providing for communication between adjacent working chambers.

10 6. In a rotary machine for pumping a fluid medium, the combination comprising a housing, a shaft journaled for rotation in said housing and having a central hub joined thereto, said hub being formed with a chamber for receiving the fluid medium therein, a plurality of stationary members fixed to said housing and formed with lateral faces, a plurality of rotary members fixed to said hub for rotation therewith and positioned between a stationary member, each of said rotary members having a tapered configuration which defines a maximum and

15 minimum thickness in the axial direction, the portions of said rotary members defining the maximum and minimum thickness being diametrically opposed, the portion defining the maximum thickness having parallel faces one of which engages one of the lateral faces of said stationary member to define regions of tangency therewith, the remaining portions of said rotary members being spaced from the lateral faces of said stationary member to define working chambers therewith, longitudinally movable abutments positioned in each of said

20 stationary members and engaging said rotary members to divide said working chambers into suction and discharge spaces, means for urging said abutments into engaging relation with said rotary members, inlet passages formed in said stationary members and communicating with said suction spaces, discharge means formed in said housing and communicating with said discharge spaces, passage means communicating with said chamber in said hub and said inlet passages for directing said fluid into said suction spaces, and passage means formed in said stationary members and communicating with said discharge

25 means for receiving said fluid from said discharge spaces, rotation of said rotary members causing said suction and discharge spaces to increase and decrease in volume respectively and thereby effect a uniform pumping action.

45 7. A rotary pump comprising a housing, a pair of stationary members, each of which is fixed to an end wall of said housing, and a third stationary member fixed to said housing intermediate said pair of stationary members, said stationary members being formed with lateral

30 faces, a pair of rotary members, one of said pair of rotary members being positioned between said third stationary member and one of said first named stationary members, said rotary members being tapered to define a maximum and minimum thickness in the axial direction,

35 55 the portions of said rotary members defining the maximum and minimum thickness being diametrically opposed, the portion defining the maximum thickness having parallel faces one of which engages one of the lateral faces of said stationary member to define regions of tangency therewith, the remaining portions of said

40 60 rotary members being spaced from the lateral faces of said stationary member to define working chambers therewith, movable members positioned in said stationary members, means for urging said movable members into

65 65 contacting relation with said rotary members, each of said working chambers thereby being divided in suction and discharge spaces that increase and decrease in volume respectively upon rotation of said rotary members, means communicating with said suction spaces for introducing

70 75 operating fluid therein, passage means formed in said stationary members for exhausting said operating fluid from said discharge spaces, and fluid conducting chambers formed between the end walls of said housing and the lateral wall of the adjacent stationary member, said fluid conducting chambers receiving fluid therein under

pressure, thereby providing for limited lateral movement of said stationary members and preventing wear thereof during high pressure operation of said pump.

8. In a rotary pump as set forth in claim 7, said fluid introducing means including a rotatable hub fixed to said rotary members and having a central inlet chamber formed therein, and passage means formed in said stationary members and communicating with said inlet chamber in the hub and said working chamber for directing fluid from said inlet chamber into said suction spaces.

9. A rotary pump comprising a housing, a plurality of stationary members disposed in said housing and having lateral faces formed thereon, at least one rotary member positioned between said stationary members, said rotary member having a tapered configuration which defines a maximum and minimum thickness in the axial direction, the portions of said rotary member defining the maximum and minimum thickness being diametrically opposed, the portion defining the maximum thickness having parallel faces one of which engages one of the lateral faces of said stationary member to define regions of tangency therewith, the remaining portions of said rotary member being spaced from the lateral faces of said stationary members to define working chambers therewith, abutment means disposed in said stationary members and contacting a lateral surface of a rotary member, said abutment means dividing said working chambers into suction and discharge areas, means communicating with said suction areas for introducing operating fluid thereto, said fluid introducing means including passage means formed in said stationary members and a rotatable hub fixed to said rotary member and having a central inlet chamber, means communicating with said discharge areas for exhausting said operating fluid therefrom, said fluid discharging means including passages formed in said stationary members, said suction and discharge areas increasing and decreasing in volume respectively as said rotary member is rotated to effect a rapid pumping action, and means for minimizing wear in said pump, said last named means including chambers formed between the housing end walls and the lateral surfaces of the adjacent stationary members, said chambers receiving high pressure fluid therein for allowing limited axial movement of said stationary members, thereby reducing the wear thereof when said pump is operating at high pressures.

10. In a rotary machine for pumping a fluid medium, a stationary member fixed in said housing, a plurality of rotary members disposed in said housing and arranged in alternate relation with respect to said stationary member, each of said rotary members having a tapered configuration which defines a maximum and minimum thickness in the axial direction, the portions of said rotary members defining the maximum and minimum thickness being diametrically opposed, the portion defining the maximum thickness having parallel faces one of which engages one of the lateral faces of said stationary member to define regions of tangency therewith, the remaining portions of said rotary member being spaced from the lateral faces of said stationary member to define working chambers therewith, axially movable abutments dis-

posed in said stationary member and contacting the side faces of said rotary members, thereby dividing said working chambers into suction and discharge spaces, means communicating with said suction spaces for introducing 5 said fluid medium thereto, said fluid introducing means including a rotatable hub secured to said rotary members and having an inlet chamber formed therein and passage means formed in said stationary members and communicating with said inlet chamber and said suction spaces, and discharge means communicating with said discharge spaces for exhausting said fluid medium therefrom, said discharge means including passage means formed in said stationary members, said suction and discharge spaces increasing and decreasing in volume, respectively, upon rotation of said rotary members, whereupon a constant volume pumping action is effected.

11. A rotary pump comprising a housing, at least one stationary member secured in said housing and being formed with lateral faces thereon, rotary members positioned in said housing in alternate relation with respect to said stationary member, said rotary members having a tapered configuration which defines a maximum and minimum thickness in the axial direction, the portions of said rotary members defining the maximum and minimum thickness being diametrically opposed, the portion defining the maximum thickness having parallel faces one of which engages one of the lateral faces of said stationary member to define regions of tangency therewith, the remaining portions of said rotary members being spaced from the lateral faces of said stationary member to define working chambers therewith, abutments disposed in said stationary member and contacting the lateral faces of said rotary members, means for urging said abutments into contacting relation with said lateral faces for separating said working chambers in suction and discharge spaces, said rotary members being formed with passages in the body thereof which provide for communication between adjacent working chambers, means communicating with said suction spaces for introducing operating fluid therein and passage means formed in said stationary member and communicating with said discharge spaces for exhausting said operating fluid therefrom.
